UNITED STATES PATENT OFFICE.

GEORGE KENSBOCK, OF EASTON, KANSAS.

GRAIN-CONTAINER FOR WAGON-BOXES.

1,243,183.

Specification of Letters Patent. Patented Oct. 16, 1917.

Application filed January 22, 1917. Serial No. 143,598.

To all whom it may concern:

Be it known that I, GEORGE KENSBOCK, a citizen of the United States, residing at Easton, in the county of Leavenworth and 5 State of Kansas, have invented certain new and useful Improvements in Grain-Containers for Wagon-Boxes, of which the following is a specification.

My invention relates to grain containers 10 for wagon boxes, and my object is to provide a flexible device of this character which may be placed in a wagon box, so that grains and the smallest seeds can be hauled without loss by leakage through the holes and cracks 15 usually existing in wagon boxes, especially after the same have been in service for a considerable period of time.

The invention also embodies means whereby the contents of the container can be 20 dumped into the hopper of a grain elevator, without waste by spillage on the ground.

Other objects of the invention will hereinafter appear, and in order that said invention may be fully understood, reference will 25 now be made to the accompanying drawings, in which:

Figure 1 is a plan view of a wagon body provided with my invention.

Fig. 2 is a vertical, longitudinal sectional view, taken on line II—II of Fig. 1.

Fig. 3 is an end view of the parts disclosed by Figs. 1 and 2.

Fig. 4 is a cross sectional view on line IV—IV of Fig. 1.

Fig. 5 is a broken detail, perspective view of the rear portion of the container.

1 designates a wagon box of the type usually employed on farm wagons and embodies side boards 2, end-gates 3, tie-rods 4 40 for holding the end-gates in place, an intermediate tie-rod 5 to prevent the side boards bulging outwardly intermediate their ends, and a bottom 6.

8 designates my container, the shape of 45 which corresponds, substantially, to the interior of the wagon box, within which it is adapted to fit as clearly shown on Figs. 1 and 2. Said container consists, preferably, of sheeting, canvas, or other strong fabric 50 and comprises a bottom 10, sides 11, and front and rear ends 12 and 13, respectively, all of which are joined in such manner as to prevent leakage of grain.

The rear end 13 is provided with a spout 55 15, having a reduced outlet 16 through which the grain or other contents of the con-

tainer can be discharged. To close the spout it is folded upwardly against the rear end 13 of the container as disclosed on Fig. 2, where it is reliably held by a pin 18 and eyelets 19 and 20 secured to the lower side of the outlet 16 and the upper portion of said rear end 13, respectively. The pin 18 is, preferably, attached by a cord 21 to the rear end 13 of the container 8, to prevent loss of 60 said pin when withdrawn from the eyelets 19 and 20, preparatory to lowering the outlet from the position disclosed by Fig. 3, to the position disclosed by Fig. 5.

The upper margins of the sides 11 and the 65 ends 12 and 13 of the container 8 are provided with hooks 23 adapted to engage the upper edges of the wagon body and thus prevent said sides and ends of the container from sagging downwardly. The hooks 23 70 also hold the upper edges of the container snugly against the interior walls of the wagon box 1 and thus prevent grain being pitched into said container from falling between the walls thereof and the walls of the 75 wagon box.

The bottom 10 of the container 8 is reinforced with metallic wear strips 25, so that when necessary, grain can be shoveled from the container without injury to said bottom 10 from contact with the hard surface of the shovel. Strips of fabric 26 are interposed between the bottom 10 and the wear strips 25 to prevent the edges of the latter cutting the former and said bottom 10 is 80 further reinforced by fabric strips 27, stitched or otherwise secured to the underside of the bottom 10 immediately beneath the strips 26.

When it is desired to use the wagon box 1 85 for hauling other farm products than grain and seeds, the container 8 can be readily removed, so that it will not be subjected to undue wear.

From the foregoing description it is apparent that I have provided means whereby the great loss of grain suffered annually by farmers throughout the country from hauling grain in leaky wagon boxes from the farm to an elevator, or shipping point, is 90 economically and effectively overcome, and while I have shown and described the preferred form of my invention, I reserve the right to make such changes in the combination, construction, and arrangement of parts 95 as properly fall within the spirit and scope 100 of the claims.

Having thus described my invention, what I claim and desire to secure by Letters Patent, is:

1. In a device of the character described, 5 a flexible container adapted to fit within a wagon box, a spout at one end of said container adapted to fold against said end, spaced eyes on said spout, spaced eyes on the end of the container arranged so as to be received in the spaces between the spout eyes and in alinement therewith, and a pin adapted to be placed in said eyes to hold the spout in folded condition.
2. In a device of the character described, 15 a flexible container adapted to fit within a wagon box, strips secured longitudinally to the upper and lower surfaces of the bottom of said container, and metallic wear strips secured to the first-mentioned uppermost strips.
3. In a device of the character described, 20 a flexible container adapted to fit within a wagon box, and metallic wear and reinforcing strips secured to the bottom of the container and on the upper face of said bottom,

said wear strips being arranged longitudinally of the bottom and formed to provide smooth faces on which a shovel may slide in removing grain from the container.

4. In a device of the character described, 30 a flexible container adapted to fit within a wagon box, metallic wear and reinforcing strips secured to the bottom of the container and on the upper face of said bottom, said wear strips being arranged longitudinally 35 of the bottom and formed to provide smooth faces on which a shovel may slide in removing grain from the container, and fabric strips alined with said wear strips and interposed between the latter and the container bottom and formed to prevent the edges of the wear strips from cutting the container bottom.

In testimony whereof I affix my signature, in the presence of two witnesses.

GEORGE KENSBOCK.
